CLAIM

The ornamental design for a wireless remote control, as shown and described.

DESCRIPTION

FIG. 1 is a top right perspective view of a wireless remote control;

FIG. 2 is a top rear perspective view thereof;

FIG. 3 is a top plan view thereof;

FIG. 4 is a bottom plan thereof;

FIG. 5 is a left side elevational view thereof, the right side elevational view being a mirror image;

FIG. 6 is a front elevational view thereof; and,

FIG. 7 is a back elevational thereof.
